[57] CLAIM

The ornamental design for a napkin disposal, as shown and described.

DESCRIPTION

FIG. 1 is a top and front perspective view of a napkin disposal showing my new design; the broken lines are for illustrative purposes only;

FIG. 2 is a front elevational view thereof;

FIG. 3 is a top plan view thereof;

FIG. 4 is a rear elevational view thereof;

FIG. 5 is a left side elevational view thereof, the right side elevational view being a mirror image of that shown; and,

FIG. 6 is a bottom plan view thereof.

FIG. 1

FIG. 2

FIG. 3

FIG. 4

FIG. 5
